UNITED STATES PATENT OFFICE.

HUBERT HENN, OF BERLIN, GERMANY, ASSIGNOR TO AMERICAN THERMOS BOTTLE COMPANY, OF BROOKLYN, NEW YORK.

DOUBLE-WALLED VESSEL.

No. 923,791.

Specification of Letters Patent.

Patented June 1, 1909.

Application filed July 24, 1908. Serial No. 445,113.

To all whom it may concern:

Be it known that I, HUBERT HENN, a subject of the German Emperor, and resident of Berlin, Germany, have invented a 5 new and useful Improvement in Double-Walled Vessels, of which the following is a specification.—

The invention relates to double walled vacuum vessels of glass or other brittle material, in which the inner and outer walls 10 are united at the mouth of the vessel and inclose between them a rarefied space.

The invention consists in the construction 15 of the device for supporting the inner wall on the outer wall when the vessel is tilted from a vertical position or subjected to lateral shock, as more particularly pointed out in the claims.

In the accompanying drawings, Figure 1 20 is a view of a double walled vessel in vertical central section with two of the improved stiffening devices applied thereto, Fig. 2 is a section taken in the plane of the line A—A of Fig. 1, and Fig. 3 is a section taken in the 25 plane of the line B—B of Fig. 1.

The outer wall 1 and the inner wall 2 are united with each other only at the mouth of the vessel and they inclose between them a rarefied space 3.

30 The upper stiffening device comprises a band ring 4 snugly embracing the inner wall of the vessel, which band ring is provided with outwardly projecting prongs 5 each engaging a stiffening block 6 of some suitable 35 non-heat-conducting material, such, for instance, as asbestos or cork. The outer faces of these stiffening blocks 6 engage the inner face of the outer wall 1, for holding the inner wall spaced from the outer wall at this point.

40 The lower stiffening device comprises a flat ring 7 surrounding the inner wall and spaced from both the inner and outer walls. This ring 7 is provided with prongs 8 uprising therefrom, each of which prongs engages a 45 stiffening block 9 of some suitable non-heat-conducting material, such, for instance, as asbestos or cork. The inner faces of these blocks 9 engage the outer face of the inner wall 2 and the outer faces of these blocks 50 engage the inner face of the outer wall 1 for holding the inner wall spaced from the outer wall. In both of these stiffening devices it will be seen that the blocks are held

permanently in position by the rings so that they can not be displaced. Furthermore, in neither of these forms does the ring bridge the space between the inner and outer walls. Therefore, these rings will not transmit the variations in temperature from the inner wall to the outer wall.

60 In order to provide a more elastic support for the inner wall at the greatest distance from the junction of the two walls at the mouth of the vessel, I arrange the lower series of stiffening blocks so that they are held from displacement by frictional contact with both walls. On the other hand as the upper series of blocks are located nearer the neck and at a point where the relative movement of the walls on tilting the vessel is less, 70 I connect said blocks positively by means of the band and prongs to the inner wall.

What I claim is:

1. The combination with a double walled vessel comprising inner and outer walls united 75 with each other only at the mouth of the vessel and inclosing between them a rarefied space, of a stiffening device comprising a ring surrounding the inner wall, said ring being provided with prongs, and spacing blocks of 80 non-heat-conducting material engaged by said prongs whereby the blocks are held against displacement.

2. The combination with a double walled vessel comprising inner and outer walls united 85 with each other only at the mouth of the vessel and inclosing between them a rarefied space, of a stiffening device comprising a ring embracing the inner wall, said ring being provided with outwardly extending prongs, and 90 stiffening blocks engaging said prongs and interposed between the ring and the outer wall for holding the inner wall spaced from the outer wall.

3. The combination with a double walled 95 vessel comprising inner and outer walls united with each other only at the mouth of the vessel and inclosing between them a rarefied space, of a stiffening device comprising a ring surrounding the inner wall and spaced from the inner and outer walls, said ring being provided with prongs, and stiffening blocks of 100 non-heat-conducting material engaging said prongs and the inner and outer walls for holding the inner wall spaced from the outer wall.

4. In a double walled vacuum vessel of the

type set forth, a plurality of supports disposed within the vacuum space and detachably connected to a wall of said vessel, and blocks of heat insulating material carried by 5 said supports.

5. In a double walled vacuum vessel of the type set forth, a plurality of supports disposed within the vacuum space and detachably connected to a wall of said vessel, and 10 blocks of heat insulating material carried by

said supports and in contact with the opposite wall.

In testimony, that I claim the foregoing as my invention, I have signed my name in presence of two witnesses, this eleventh day of 15 July 1908.

HUBERT HENN.
